UNITED STATES PATENT OFFICE.

BERRY B. SIMONS, OF NEW YORK, N. Y., ASSIGNEE TO AUTO SIGNALITE COMPANY, A CORPORATION OF NEW YORK.

SIGNALING DEVICE.

1,114,543.

Specification of Letters Patent.

Patented Oct. 20, 1914.

Application filed June 20, 1913. Serial No. 776,649.

To all whom it may concern:

Be it known that I, BERRY B. SIMONS, a citizen of the United States, and a resident of New York city, in the county of New 5 York and State of New York, have invented new and useful Improvements in Signaling Devices, of which the following is a specification.

This invention relates to signaling devices, 10 more particularly to the formation of the display member and the characters thereon.

One object of the invention is to provide a signal drum which can be made very cheaply with the signal characters molded 15 therein.

Another object is to provide a formation 20 of characters and surrounding background, so that a paint or coloring liquid may be applied to the background or characters without danger of the liquid or coloring applied to the one running onto the surface of 25 the other.

The various further objects and advantages will more fully appear from the detailed description and the features of novelty will be particularly pointed out in the 30 claims.

In the drawing illustrating this invention, Figure 1 is an elevation of the signal member as it appears when finished. Fig. 2 is an elevation illustrating the device with the first coating of opalescent paint applied 35 thereon. Fig. 3 is an end view of the device. Fig. 4 is a fragmental section on an enlarged scale taken along line 4-4 of Fig. 2.

The display member consists preferably of a drum which may be rotated by suitable means to present to view various display surfaces. The signal is particularly adapted 40 for illumination by suitable illuminating means such as described in the patent of William J. Bauer, Number 1,086,838, dated July 29th, 1913. The signal member is accordingly made of transparent material such as 45 glass blown into the form of a drum with the signal characters sunk in the body of the material during the process of the formation of the drum. Thus the latter may be blown into a die having the desired characters raised on the interior walls thereof. 50 Also the portions of the drum adapted for attachment to the parts of the holder and the actuating means for the same may likewise be blown right into the mold.

Referring particularly to the drawing, the 55 drum is formed preferably with a polygonal section having the sides 10 upon which the signal characters are formed and the beveled edges 11 which are left transparent, according to the co-pending application above referred to, and the transverse ends 12 upon which are formed threaded annular trunnions 13. These ends stiffen the drum considerably and the threaded trunnions serve as convenient means for fastening the actuating device to the drum, either on the right or on the left hand side. The latter is advantageous when the signal is used on automobiles as set forth in the co-pending application above referred to and makes it possible 60 to readily adapt the drum for the type of car in which the steering gear is situated on the right of the vehicle or the type in which the steering gear is situated on the left of the vehicle. The display characters, 65 together with the background 14 therefor, are preferably sunk upon the side 10 of the drum and the characters sunk comparatively 70 deeper than the background.

Referring to Fig. 4, the surfaces 15, corresponding to the legs of the "R" and the surface 16 corresponding to the "I", are illustrated as sunk below the background 14. These sunk letters are surrounded by ridges 17, which separate the same from the 75 background. Thus, in finishing the drum, an opalescent coating is first applied over the letters and background as indicated in Fig. 2, and then a dark coloring or paint is applied to the background. This coating 80 for the background may be applied with comparatively little care as the ridges effectually prevent any of the paint from flowing over onto the surface of the characters. In this way, the drum may be finished by comparatively unskilled help and thus reduces the cost of manufacture. If 85 desired, a very fluid paint may be used for the background, which needs to be applied only approximately, and after so applied, 90 will flow to cover the entire surface of the background up to the ridges which retain the same and prevent it from overflowing over onto the characters. These ridges also 95 serve to set off the characters more prominently and sharply, rendering the same more distinct, especially when illuminated from within. They also serve to protect the characters.

acters from abrasion by spacing them from any foreign body that may accidentally impinge upon that portion of the drum.

Preferably, I coat the end portions of 5 the sides of the drum with a red coating 18 which constitutes the danger signal of the ordinary tail lamp used on vehicles, and thus all of the signals necessary may be indicated on the various surfaces of the 10 drum itself.

From the above description, it will be clear that I have provided a signal drum which may be made very cheaply and any finishing which may be required, may be 15 accomplished with a minimum exercise of skill, thus facilitating the rapidity as well as decreasing the cost of manufacture. Moreover, the characters are always sharply defined and a very clear signal is thus 20 obtained.

Having thus described my invention, I claim as new and desire to secure by Letters Patent:

1. A signal drum of transparent material 25 having a display side, a background formed on said side, signal characters sunk below the outer surface of the background and ridges surrounding the characters, and a

coating covering the background and setting off the characters, said ridges serving as a 30 protection for the characters.

2. A signal drum of transparent material having a display side, signal characters formed on said side, a background surrounding said characters, ridges surrounding the 35 characters and separating the same from the background, the characters being adapted to transmit light therethrough, and a dark coating on the background for setting off the characters, the said ridges serving as a 40 protection for the signal characters and also increasing the distinctiveness of the characters.

3. A signal device comprising a transparent member having a display surface, a 45 background sunk below said surface, signal characters sunk below said background, and ridges surrounding the characters and separating the same from the background.

Signed at New York city, in the county 50 of New York and State of New York this 28th day of June A. D. 1918.

BERRY B. SIMONS.
